UNITED STATES PATENT OFFICE.

JOSEPH A. ROSENFELD AND HARRY ROSENFELD, OF CLEVELAND, OHIO.

CLOTH-CUTTING AND PATTERN-MARKING MACHINE.

1,398,396.

Specification of Letters Patent. Patented Nov. 29, 1921.

Application filed March 28, 1921. Serial No. 456,291.

To all whom it may concern:

Be it known that we, JOSEPH A. ROSENFELD and HARRY ROSENFELD, citizens of the United States, residing at Cleveland, in the county of Cuyahoga and State of Ohio, have invented certain new and useful Improvements in Cloth-Cutting and Pattern-Marking Machines, of which the following is a specification.

10 This invention relates to cloth cutting and pattern marking machines, and has for its main object to provide a cloth cutting machine which will mark a pattern like the design being cut.

15 Another object of the invention is to provide a cloth cutting machine, having in combination with the cutting knife a needle for perforating paper to mark a design.

20 A further object of the invention is to provide a cloth cutting and perforating machine, which will ink the perforations to more distinctly mark the pattern.

25 With the above and other objects in view, the invention will be hereinafter fully described as illustrated in the accompanying drawings, and the novel features thereof will be distinctly pointed out in the appended claims.

30 In the drawings similar characters of reference are used to designate corresponding parts.

Figure 1 is a side elevation of a cloth cutting and pattern marking machine constructed in accordance with our invention, 35 Fig. 2 is a front elevation of the machine, Fig. 3 is an enlarged view illustrating the base portion of the machine with the cutting knife in its down position,

40 Fig. 4 is a sectional view taken on line 4—4 of Fig. 3, and Fig. 5 is a similar view taken on line 5—5 of Fig. 3.

45 Referring to the drawings 1 represents a base supported by rollers 2 and having an inclined forward end. Fixed to said base is an up-right 3, which supports a platform 4 carrying an electric motor 5 having a shaft 6. A handle 7 is fixed to the rear end of the platform 4 for pushing and guiding the 50 machine during its operation. Current may be supplied to the electric motor through the handle 7 as indicated at 8, and a suitable switch 9 is located thereon. At the forward end of the platform is a head 10,

and in this head is slidably mounted a vertical bar 11, which is reciprocated by the motor 5, and carries a cutting knife 12. The bar 11 is adjustably connected at 13 to a head 14, which is eccentrically pivoted at 15 to a flange 16 fixed to the motor shaft 6. An ordinary pressure foot 17 is adjustably supported in the head 10 by means of a set screw 18.

The cutting knife 12 is slidably mounted in a guide-way 19 of the up-right 3, its rear edge being enlarged at 20 for this purpose. The forward edge of the cutting knife 12 is sharp, and extended below its lower end is a needle 21 for perforating paper to mark a pattern. The lower end of the knife 12 is recessed at 22 thereby leaving a forward portion 23, and a rear portion 24 which is the same dimension as the needle 21 and forming a part thereof. Said forward portion 23 of the cutting knife 12 is adapted 75 to pass through a slotted opening 25 of the base 1 and the rear portion 24 of the cutting knife and the needle 21 through an aperture 26 of said base. The solid part 27 of the base projects thereabove. In order that the 80 perforations made through the sheets of paper as 28 may be more distinct, ink from a suitable reservoir 29 supported upon the platform 4 is directed to the needle 21 by means of a tube 30 having a closed end 31, 85 and provided with vertical alining openings at 32, through which said needle passes. The flow of the ink may be regulated or entirely shut off at 33 of the reservoir in the ordinary manner.

90 In practice, the sheets of paper 28 to be marked as patterns are laid upon a table and the base 1 of the machine placed upon said sheets of paper, and between the same and the stack of cloth as 34 to be cut. The flow 95 of the ink is regulated, and the operator pushes and guides the machine by means of the handle 7, to cut the cloth according to a certain pattern as is the usual custom. At the same time that the cloth 34 is being cut by the reciprocating knife 12, the needle 21 is perforating the sheets of paper 28, and as the needle passes through the openings at 32 of the tube 30, it carries ink to the perforations made in the sheets of paper 28 thereby marking the same with the exact 100 pattern being cut. The sheets of paper 28 now having a pattern thereon, may in turn

be used as a pattern for cutting cloth. This saves the time of laying out a pattern.

Having fully described our invention, what we claim is:

- 5 1. In a pattern marking machine, the combination of a needle for making perforations to mark a design, means for reciprocating the needle, a reservoir for a marking fluid, a tube leading from the reservoir, 10 and the tube having alining openings in its wall for the passage therethrough of the needle, substantially as described.
- 15 2. In a cloth cutting and pattern marking machine, the combination of a knife, means for actuating the knife, and the knife actuating a needle for making perforations to mark a design, substantially as described.
- 20 3. In a cloth cutting and pattern marking machine, the combination of a knife, means for actuating the knife, the knife actuating a needle for making perforations to mark a design, and a means for directing a marking fluid to the needle, substantially as described.
- 25 4. In a cloth cutting and pattern marking machine, the combination of a knife, means for actuating the knife, the knife actuating a needle for making perforations to mark a design, a reservoir for marking fluid, a 30 tube leading from the reservoir, and the tube having openings for the passage there-

through of said needle, substantially as described.

5. In a cloth cutting and pattern marking machine, the combination of a reciprocating knife, means for actuating the knife, the end of the knife being recessed longitudinally, the portion of the knife at one side of the recess serving as a needle, a tube for directing ink to the needle, and the tube 35 40 being provided with openings for the passage therethrough of the needle, substantially as described.

6. In a cloth cutting and pattern marking machine, the combination of a base, an up-right extending from the base, a platform fixed to the up-right, a motor supported upon the platform, a knife blade reciprocated by the motor, the knife blade having a needle for making perforations to 45 50 mark a design, the end of the knife blade being recessed longitudinally, the portion of the knife blade at one side of the recess serving as a needle, a tube for directing ink to the needle, and the tube being provided with 55 openings for the passage therethrough of the needle substantially as described.

In testimony whereof we affix our signatures.

JOSEPH A. ROSENFIELD.
HARRY ROSENFIELD.
